Primary Examiner — Catherine S Posthauer(74) *Attorney, Agent, or Firm* — Todd R. Miller(57) **CLAIM**

The ornamental design for a container base, as shown and described.

DESCRIPTION

FIG. 1 is a top perspective view of a container base showing our new design;

FIG. 2 is a top view thereof;

FIG. 3 is a side view thereof; and,

FIG. 4 is a bottom view thereof.

The broken lines are shown for the purpose of illustrating parts of the article that form no part of the claimed design.
